UNITED STATES PATENT OFFICE.

JOHN EDWARD OGDEN, OF CORNWALL, NEW YORK.

ADJUSTABLE CONCRETE-INSERT.

1,365,718.

Specification of Letters Patent. Patented Jan. 18, 1921.

Application filed June 28, 1919. Serial No. 307,398.

To all whom it may concern:

Be it known that I, JOHN EDWARD OGDEN, a citizen of the United States of America, and a resident of Mountainville, town of 5 Cornwall, Orange county, and State of New York, have invented certain new and useful Improvements in Adjustable Concrete-Inserts, of which the following is a specification, reference being had to the 10 accompanying drawings, forming a part thereof.

This invention relates to concrete inserts which are adapted to be embodied in concrete slabs of different thicknesses by means 15 of which inserts, bolts or screws may be affixed to the finished structure, and its object is to provide a simple and inexpensive device for this purpose. More specifically, its object is to provide an adjustable device of 20 this character which is especially adaptable for use in slabs of different thicknesses. These and other objects of the invention will appear in the following specification, in which I will describe the invention and the 25 novel features of which will be set forth in appended claims.

Referring to the drawings:

Figure 1 is a sectional elevation of a device which is made according to and embodies this invention. In this figure, a molding board is shown together with a part 30 of a concrete structure, both of the latter parts being also shown in section.

Fig. 2 is a sectional plan view of the same 35 device, the section of this figure being taken on the line 2-2 of Fig. 1.

Fig. 3 is a sectional elevation of the device 40 shown in the preceding figures with the parts thereof shown in different relative positions. In this figure a part of the molding board is shown together with a device for easily centering the insert.

Fig. 4 is an elevation of a modified form 45 of construction which also embodies this invention. In this figure certain parts are broken away to more clearly illustrate their construction.

Fig. 5 is an elevation partly in section of another modified form of construction.

50 Fig. 6 is an elevation of a still further modification.

Like characters of reference designate corresponding parts in all the drawings.

10 designates a molding board upon which 55 a concrete body is to be formed, in this par-

ticular case a floor slab, a part of which is shown at 11.

12 is a cylindrical member preferably pressed out of sheet metal. The upper end of this member is closed as at 13, and at its 60 other end the metal is bent outwardly to form flanges 14 with stiffened ribs 15 formed between the body of the device and the flanges. In the flanges are formed indentations or notches 16. The lower portion of 65 this member has a smooth cylindrical wall 17, but the upper portion of it is crimped or corrugated to form screw threads 18 on both the inside and outside of the tube.

20 is an open ended cylindrical member 70 with its walls crimped or corrugated through the length thereof to form screw threads which fit the threads 18 on the outside of the member 12. This member 20 also has an outwardly projecting flange 21 at its 75 lower edge.

In Fig. 3 a tapered plug 19 is shown removably affixed to the molding board 10.

Before specifically describing the devices shown in the other figures of the drawings, 80 I will describe the way in which this device is used. Before a concrete floor, for example, is made forms are prepared for the reception of the plastic concrete. The molding board 10 is a part of one of such forms. 85 At such points as is desired to have screw sockets in the finished structure, inserts are placed. These may be affixed to the molding board by tacks in the notches 16 as shown in Fig. 1, or may be positioned by being 90 placed over the tapered plugs 19 which are first fastened to the board 10 at the desired points, as shown in Fig. 3.

The concrete slabs vary in thickness, and as it is desirable to have the length of the 95 device varied and the flanges 14 and 21 separated different amounts in structures of different thicknesses, the member 20 is turned on the member 12 to vary its position thereon.

In Figs. 1 and 3 the member 20 is shown 100 in two of its positions, and it is obvious that it is adjustable through a great range. As shown in Fig. 1 the device is adjusted for use in a comparatively thick concrete slab. In 105 this case the cylindrical threaded part above the member 20 extends above the closed upper end of the part 12. The result is that some of the concrete enters the space between the wall of member 20 and the top 110

13 of the member 12. This part is designated 11^A and serves to hold the device in an upright position, and to strengthen its hold in the concrete.

5 In Fig. 3 the parts are in different relative positions as used in comparatively thin slabs.

Thus with this device it is not necessary to provide inserts of a plurality of lengths for different thicknesses of concrete but inserts of standard size may be readily adjusted to meet different conditions. After the concrete has set and the molding board 10 removed, screws or bolts may be inserted in the sockets formed by the inserts and their threads will engage the threads 18 on the inside of the member 12. The threads on the outside had previously been used for the purpose of adjusting the position of the member 20 on the member 12.

20 In the device shown in Fig. 4 the inner or lower flanged member 30 is open at both ends. It is shown crimped or corrugated through its length to form screw threads on the inside and on the outside of the cylindrical wall. The outer or upper flanged member 31 is closed at the top as at 32 and is crimped or corrugated throughout its length to form threads which fit over the threads 30 on the outside of the lower member. It 30 may be seen that in this case the distance between the flanges and the members 30 and 31 may be varied by simply imparting relative rotation between these members. It is also obvious that the upper member may be 35 made of smaller diameter than the lower member so as to screw inside the same in which case its flanged end will be uppermost as in the case of the upper member shown in Fig. 5. It is also clear that a 40 screw or bolt may engage the threads inside of the member 30 after the concrete structure is finished.

Fig. 5 is an illustration of a device which comprises a cylindrical member 40 the outer 45 surface of which is threaded near its ends and at least one end of which is also threaded on the inside, as at 41. Two similar flanged end pieces 42 and 43 are screwed onto the cylindrical member desired amounts 50 to vary the length of the assembled device and the distance between its flanges. A plug 44 is driven into the upper end of member 40 to prevent the entry of any concrete. After the device is embedded in a concrete structure a bolt may be inserted in the threads 41.

The cylindrical member 12 in Fig. 6 is similar to that shown in Figs. 1 and 3, but in this case the part 50 is a flange of double thickness metal engaging the outer surface 60 of member 12, and preferably threaded internally so that its position on the member 12 may be adjusted by rotating it.

This invention is capable of many variations and modifications, some of which have 65 been illustrated and described to show prac-

tical embodiments thereof and while most of the structures shown are of pressed metal, the invention is not necessarily limited to devices of this particular form of construction. I intend no limitations other than those imposed by the appended claims.

What I claim is:

1. A concrete insert comprising a tubular sheet metal member having the wall thereof crimped to form corresponding internal and external screw-threads and open at the end which is exposed to receive a bolt having screw-threads to fit the internal screw-threads and another tubular sheet metal member having a laterally projecting flange 75 at one end to operate as an anchorage and having the wall thereof crimped into the form of screw-threads to fit the screw-threads of the first member, whereby said second member may be screwed on the first member to carry the outstanding flange to different positions to suit different thicknesses of concrete with which the insert is used and one of said members being closed at the end to exclude the concrete from the 80 screw socket formed by the first member.

2. A concrete insert comprising a tubular body threaded internally and externally, a flange projecting from said body and another flanged threaded tubular body engaging the external threads on said first body.

3. A concrete insert comprising a tubular sheet metal member open at the end which is to be exposed and closed at the opposite end to exclude concrete, the wall of said 100 sheet metal member being crimped to form corresponding internal and external screw-threads and an open-ended tubular sheet metal member crimped to form screw-threads fitting over the external screw-105 threads of the first member, said second member having an outstanding flange and reversibly engageable over the screw-threaded exterior of the first member to position the flange in different relations on the first 110 member.

4. A concrete insert comprising a tubular body crimped throughout at least a part of its length to form screw threads on its inner and outer surfaces, said body being bent 115 outwardly at one end to form a flange, and another tubular body of sheet metal bent outwardly at one end to form a flange, crimped to form threads adapted to engage the threads on the outer surface of said first 120 member.

5. A concrete insert comprising a tubular body crimped throughout at least a part of its length to form screw threads on its inner and outer surfaces, said body being 125 bent outwardly at one end to form a flange, and another tubular body of sheet metal bent outwardly at one end to form a flange, crimped to form threads adapted to engage the threads on the outer surface of said first 130

member, one of said members being closed at the end thereof opposite its flange.

6. A concrete insert comprising a tubular sheet metal body closed at one end, crimped throughout at least a part of its length to form screw threads on its inner and outer surfaces, said metal being bent outwardly at the other end to form a flange, and an open ended tubular member of sheet metal 10 crimped throughout its length to form threads adapted to engage the threads on the outer surface of said first member, and an outwardly extending flange on said open ended member.

15 7. A concrete insert comprising a tubular sheet metal body closed at one end, crimped throughout a part of its length to form screw threads on its inner and outer surfaces and having a smooth surfaced portion 20 near its other end, said metal being bent outwardly at said other end to form a flange constructed to form notches in the edges thereof, and an open ended tubular member of sheet metal crimped throughout its 25 length to form threads adapted to engage the threads on the outer surface of said first member, and an outwardly extending flange on said open ended member.

8. A concrete insert comprising a tubular 30 sheet metal body closed at one end, crimped throughout a part of its length to form screw threads on its inner and outer surfaces and having a smooth surfaced portion near its other end, said metal being bent 35 outwardly at said other end to form a

flange, and an open ended tubular member of sheet metal crimped throughout its length to form threads adapted to engage the threads on the outer surface of said first member, and an outwardly extending flange 40 on said open ended member, combined with a centering plug adapted to be secured to a molding board and to fit within the smooth surfaced part of the first member.

9. A concrete insert comprising a tubular sheet metal member open at the end which is to be exposed and closed at its opposite end, said member having a laterally projecting positioning flange at its outer exposed end, having a smooth surfaced portion at 50 the entrance to the socket therein and having the balance of the wall thereof, from said smooth surfaced portion to the closed end, crimped to form corresponding internal and external screw-threads, the internal 55 screw-threads providing a screw socket to receive the threaded portion of a screw bolt and a laterally projecting flange member threaded to fit over the external screw-threads of the screw socket member and adjustable thereover for the full length of the screw-thread portion of the socket member 60 for positioning the same to different thicknesses of concrete.

In witness whereof I hereunto set my hand this 26th day of June 1919.

JOHN EDWARD OGDEN.

Witness:

I. B. MOORE.
